UNITED STATES PATENT OFFICE

CHARLES B. RUMSEY, OF TAMPA, FLORIDA, ASSIGNOR TO L. B. SKINNER MANUFACTURING CO., OF DUNEDIN, FLORIDA.

BOX-PRESS.

1,163,466.

Specification of Letters Patent.

Patented Dec. 7, 1915.

Application filed March 27, 1915. Serial No. 17,374.

To all whom it may concern:

Be it known that I, CHARLES B. RUMSEY, a citizen of the United States, and a resident of Tampa, in the county of Hillsboro and 5 State of Florida, have invented a new and Improved Box-Press, of which the following is a full, clear, and exact description.

My invention relates to presses used for clamping and pressing down the covers of 10 boxes while being nailed, and in its preferred form the invention is more particularly designed for use in securing the covers of orange and like boxes. In the use of presses of the indicated character, the filled 15 boxes are received at the press in regular succession, and the periodicity of delivery is such as to make it incumbent on the workman to position the boxes, clamp and nail the covers, and release the covered boxes, all 20 with unfailing regularity and despatch.

For the purpose of carrying out the objects of my invention, clamp elements are mounted for movement to and from the box support of the press, as usual, and to have, 25 in addition, a secondary sliding movement in the direction of their axes.

The invention will be particularly described in the specific description following.

Reference is had to the accompanying 30 drawings forming part of this specification, in which similar characters of reference indicate corresponding parts in all the views, and in which:

Figure 1 is a front elevation of a box 35 press provided with my improved clamping means; and Fig. 2 is a transverse vertical section on the line 2—2 of Fig. 1.

In carrying out my invention in practice, 40 in accordance with the illustrated example, a frame 10 is provided having means to support a box as indicated in dotted lines in Fig. 2 and designated by the letter A. In the example shown the box support comprises a front frame member 11, a rear member 45 12, the front frame member having preferably a wear plate 13 and the rear member 12 having a wear plate 14 of angle iron whereby the vertical flange thereof will form a stop to position the box A. In order 50 to clamp the box on its support, clamp elements 15 are provided in the form of elongated rods or arms; these are mounted slidably in sleeve bearings 16. The bearings 16 are formed upon vertically reciprocating

rods 17 having guided movement on the 55 frame 10 whereby to carry the clamp elements 15 toward and from the box support to clamp the box or to release the same. With the presses for orange boxes and the like, the clamps 15 and their actuating means 60 are duplicated at each side, the reciprocating rods 17 being located at the back of the press so that the box may enter from the front, and the elements 15 being disposed in position to engage the box cover adjacent to 65 each end.

The illustrated means for guiding the upright rods 17 comprise upper brackets 18 and lower brackets 19 secured to the frame 10 and through which the rods 17 pass. 70

Suitable means are provided to reciprocate the rods 17, there being shown for this purpose a foot lever 20 secured to the shaft 21 having suitable bearings in the frame 10 at the back of the press. The upright rod 75 17 at one side of the press is connected by a link 22 with the foot lever 20 through the medium of a bracket 20^a secured to said foot lever. The upright rod 17 at the opposite side of the press is connected by a link 22^a 80 with a forwardly extending arm 23 on the rock shaft 21 through the medium of the bracket 23^a. Thus the arrangement is such that the single foot lever simultaneously actuates the two upright rods 17 through the 85 medium of the rock shaft 21. The depression of the foot lever 20 is in opposition to a retractile spring 24 secured to said lever at the lower end and at its upper end to a cross-bar 25 or equivalent fixed element on 90 the frame 10. Any approved means may be provided to hold the foot lever 20 in the depressed position, there being shown for the purpose a foot pawl 26 on said lever adapted to engage a toothed sector 27 which is 95 hung at its upper end as at 28 on the frame, and extends through a slot 20^b formed in the foot lever.

In order to give a sliding movement to the clamp elements 15 in their bearings 16 simultaneously with the vertical reciprocating movements imparted to said clamp elements by the upright rods 17, I provide a lever 29 for each clamp element 15. Each lever 29 is fulcrumed near its lower end on a set collar 100 30 secured to the adjacent rod 17. The upper end of each lever 29 is connected by a link 31 with the rear end of a clamp element

15, the latter having a lateral stud 32 to which said link is pivoted. Means to rock the lever 29 may consist of rollers 33 disposed on the machine in position to engage 5 the levers 29 as the latter are reciprocated with the upright rods 17. I have shown the rollers 33 mounted on studs 34 formed on arms 35 which are integral with the lower guide brackets 19. Adjacent to the fulcrum 10 of each lever 29 the same is formed with a depression as at 29^a and a bell crank arm 29^b on each lever is under the influence of a retractile spring 36, the springs being connected respectively with the said crank arms 15 29^b and with the rods 17 as at 37.

With the described construction the springs 24 normally tend to maintain the foot lever 20 in the raised position indicated in dotted lines Fig. 2, in which position the bearings 16 will be raised and the clamp elements 15 will be in the retracted position indicated in dotted lines Fig. 2, so that a box A arriving at the press may be properly positioned without any interference from the said clamp elements 15. Upon the foot lever being depressed, the upright rods 17 will be drawn downward and will carry downward the clamp elements 15. In the downward movement of the rods 17 the levers 29 will have engaged the rollers 33 and will be rocked forwardly, thereby sliding the clamp elements 15 forwardly to project the same over the box A until said clamp elements have been brought down 35 firmly against the box A at the opposite ends thereof. Upon a release of the foot lever 20 the springs 24 will raise the same and cause the upright rods 17 to rise. When the depressed portion 29^a of the levers 29 40 arrives at the rollers 33, the springs 36 will rock the levers outwardly to retract the clamp elements.

Having thus described my invention, what I claim as new and desire to secure by Letters Patent, is:

1. In a box press, a box support, a presser arm adjacent to the box support, means for giving said presser arm up and down movement relatively to the support, and means to 45 impart sliding movement to the said presser arm in the direction of its axis.

2. In a box press, a box support, a presser element and manually controlled means for imparting parallel movement to the said presser element relatively to said support and means for sliding said element to project the same over the said support or to cause it to recede from the projected position.

3. In a box press, a box support, a presser member above the support, means to raise and lower the said presser member, and

means to slide the said member longitudinally.

4. In a box press, a box support, a vertically reciprocating element at the back of the box support, and a presser member carried by the reciprocating member and slideable thereon to a projected position above the support or to a retracted position out of line with the support, and means to give sliding movement to said presser member.

5. In a box press, a box support, a presser arm above and approximately parallel with said support to press a box thereon, a bearing in which the said arm is slideable, means to raise and lower the bearing relatively to the support, and means to slide the arm in the bearing.

6. In a box press, a frame having a box support, a guide on the frame at a side of the support, an upright bar slideable in said guide and provided with a head at a higher elevation than the box support, a presser arm slideable in said head parallel with the support, a lever fulcrumed on the upright bar, a connection between the lever and the presser arm, means to raise and lower the upright arm, and means to rock the lever to slide the presser arm.

7. In a box press, a box support, clamp elements to clamp a box on the support, and means to reciprocate said elements toward and from the support and means to impart sliding movement to said elements simultaneously with the reciprocating movements to dispose them in a position projecting over the support, or in retracted position.

8. A box press comprising a box support, clamp elements, vertically reciprocating means near the back of the press at each side, separate clamp means carried by said reciprocating means in position to engage a supported box near each end, said clamp elements being slideable in the direction of their axes, to positions over the support or to retracted positions, and means to impart sliding movement to said clamp elements.

9. In a box press, a box support, reciprocating upright rods near the back of the support at each side of the press, elongated clamp elements carried by said rods and slideable therein, means to reciprocate said rods, toward and from the box support, and means to impart sliding movement to said clamp elements.

In testimony whereof I have signed my name to this specification in the presence of two subscribing witnesses.

CHARLES B. RUMSEY.
